[57] CLAIM

The ornamental design for a bracket for a siren module,
as shown and described.

DESCRIPTION

FIG. 1 is a perspective view of a bracket for a siren module showing our new design, with the broken line
showing for illustrative purposes only and forming no
part of the claimed design;

FIG. 2 is a top plan view thereof;

FIG. 3 is a rear elevational view thereof;

FIG. 4 is a left side elevational view thereof;

FIG. 5 is a right side elevational view thereof;

FIG. 6 is a bottom plan view thereof; and,

FIG. 7 is a front elevational view thereof.
